TEMPERATURE CONTROLLED SHUT-OFF
VALVE

Charles Raymond Ross, Vancouver, British Columbia, Canada

Application July 16, 1936, Serial No. 91,010

4 Claims. (Cl. 137—162)

This invention relates to a temperature controlled shut-off valve for use upon gas and oil lines, for purposes of shutting off the supply in case of fire or other high temperature hazards.

It is a fact well known to underwriters and municipal authorities that there is a considerable fire hazard incurred where gas is laid upon premises, through inability of shutting off the local supply at the point of entry in case of fire.

It is a further fact that, up to the present date, there has been no device available for this purpose that could be considered a commercial possibility by reason of the high cost of such products, which have usually been of a complicated structure.

Also in the oil fields there has been a great need for an automatic shut-off valve that had temperature control features incorporated therein, that could be produced at a reasonable cost, and it is one of the objects of my invention to supply such a device that will meet with underwriters' and municipal authorities' approval, and fulfil all of the functions of a device of this character, which can also be produced at a reasonable cost.

My invention is strictly in the nature of a safety device for installation upon all lines carrying gas, oil, or other inflammable liquids, or vapors, and is designed to operate and shut off the supply in case of any high temperature rise, either remotely or adjacent the installation of the device.

My invention and the nature of same are more fully described in the following specification and illustrated in the drawing accompanying and forming part of this application, and in which:

Figure 1 is a cross sectional elevation of valve, showing mounting of valve and valve stem and upper control chamber and control lever holding valve in the open position.

Figure 2 is an outside elevation of valve showing mounting of fusible plug upon the side of valve.

Figure 3 is a longitudinal cross sectional view of valve taken on line 3—3 of Figure 2.

Figure 4 is a sectional detail view of valve headed control rod mounted in boss at lower end of valve body head, and shows fusible plug or button mounted upon end of boss to form a keeper to said control rod. Insulation is shown surrounding the base of fusible button. Seat for the valve formed upon end of control rod is shown.

In the drawing like numerals indicate like parts, and the numeral 1 indicates the valve body head having a threaded portion 2 upon the

lower end, adapted for screwing into a valve body 3 having a seat 4 formed therein.

The valve body 3 is of conventional type, known as a globe valve.

The upper portion of the valve body head 1 is divided off from the lower part by a partition or floor 5 to comprise an upper control chamber 6 and a valve stem chamber 7 below the partition or floor 5.

Formed integrally with the floor 5 within the valve stem chamber 7 is a dependent valve stem 9, the guide 8 in which is mounted a valve stem 9, the upper end of which extends through the floor or partition 5 into the upper control chamber 6.

The lower end of the valve stem has swivelly mounted thereon a valve disc 10 adapted for seating upon the valve seat 4 formed interiorly of the valve body 3.

Mounted upon top of the valve disc 10 is a helical compression spring 11 which surrounds the dependent valve stem guide 8 and is compressed between the under side of the partition or floor 5 and the top of the swivel valve disc 10.

The upper end 12 of the valve stem 9 above the floor 5 is fitted with an odd pitched thread 13 upon which is screwed an adjustable contact disc 14 adapted to make contact with the cam head 15 of a dependent lever arm 16 pivoted upon the pin 17 mounted in bearings 18 in the upper control chamber 6.

The pin 17 is fitted into its bearings 18 from the outside of the valve body head and the pin is retained therein by a blind screw 19.

The upper control chamber 6 is closed by a threaded cover plate 20.

The contact disc 14 and valve stem 9 are supported in the open position by the cam head 15 and lever arm 16 being retained in a fixed position by a control rod 21 mounted in a boss 22 formed exteriorly upon the lower part of the valve body head 1. (See Figure 1.)

The control rod 21 has formed upon its inner end a valve head 23 adapted to seat upon a valve seat 24 formed upon the inner wall of the valve stem chamber 7 when the dependent lever arm 16 has been forced to a position to permit closing of the valve, thereby sealing any escape of gas from the interior of the valve.

The control rod 21 is retained in contact with the lower end of the dependent lever arm 16 by a fusible plug or button 25 mounted upon the end of the boss 22 and retained thereon by a threaded cap 26 fitting the boss 22.

The dependent lever arm 16 extends downwardly from the upper control chamber 6 and

into the valve stem chamber 7 through an aperture 27 formed in the floor or partition 5.

5 Formed on top of the cam head 15 is a shoulder or buttress 28 having a small projection formed thereon for the mounting of one end of a helical compression spring 29, the opposite end of the spring being positioned and compressed against the inner wall of the upper control chamber 6 so as to cause the cam 15 and 10 dependent lever arm 16 to fly into the valve closing position when the lower end of the dependent lever arm is released of restraint by movement of the control rod 21.

The cam head 15 of the dependent lever 16 is so profiled that a very small movement of the latter and lever arm 16 is necessary for it to disengage the screwed contact disc 14 upon top of the valve stem 9 and permit of the valve disc 10 to close upon its seat 4.

20. In operation the temperature control valve is intended for installation between the regular shut off service cock and a gas meter, or between any source of supply of inflammable liquid and its delivery point.

25 When so installed the valve is put into the open position by the service men unscrewing the cover plate 20 and cap 26 holding the fusible plug 25 and then by use of a special key having a shank threaded to correspond with the odd pitched thread 13 formed on top of the valve stem 9, will lift up the spring loaded valve stem and valve from off its seat 4 and set the lever arm 16 in position so that the cam 15 will support the contact disc 14 and valve stem in the

35 valve open position by moving back the end of the dependent lever arm 16 into the valve stem chamber 7 by means of the control rod 21, and then securing the control rod 21 in its guide by the fusible plug or button 25 held by the cap 40 26 so that, when the key which has opened the valve is removed, the downwards pressure of the spring loaded valve stem 9 is exerted against the cam head 15 and the lever arm 16 exerts pressure against the end of the control rod 21, 45 and through that against the fusible plug 25 in an effort to fly to the valve closing position.

This effort of the lever arm 16 to fly into the valve closing position is augmented by the helical spring 29 mounted above the cam head 15.

50 The fusible plug or button 25 may be made to melt at a very low temperature, and still be strong enough to support the thrust of the control rod 21 mounted in the boss 22.

In some installations where it is desired to establish remote control of the temperature shut-off valve by installation of thermostats, the fusible plug 25 is provided with insulation 30 surrounding the base and outer sides of the plug for the purpose of insulating the latter from contact with the valve body.

The plug 25 has a hole 31 formed in the centre of the head, in which is connected one end of an open electric circuit wire by merely caulking the soft metal comprising the plug 25 around the end of the wire. The other end of the open circuit wire is run to one side of a thermostat or a series of them not shown, and the other side of the thermostat is grounded by a ground line 32 secured at any convenient point upon the body of the valve.

In the event of any thermostat in the circuit or series functioning by a rise in temperature, such action will result in the electric circuit being closed and the melting of the fusible plug releasing the control rod 21, which in turn re-

leases the dependent lever arm 16 and permits it to fly to valve closing position.

By the moving of the lever arm 16, this action has caused the valve head on the control rod 21 to seat upon its seat 24 formed upon the inner wall of the valve stem chamber 7 and hence any gas within the valve body is prevented from leaking along the stem and guide of the control rod. 5

After the shut-off valve is once set it is complete protection against fire, as in the event of a sudden rise in temperature adjacent the meter upon which the valve is installed, the fusible plug 25 melts, and the lever arm 16 flies out and permits the valve to close and shut off the gas supply to the meter.

The object of the odd thread 13 upon the upper end of the valve stem 9 is to prevent any unauthorized person, who removes the cover plate 20 from off the top of valve body head, from moving up the valve stem 9 with a standard threaded device.

Once the valve has closed, either through accident or cause, it cannot be opened again except by an authorized party who has a key for that purpose, as the screw cap can be prevented from being removed by a sealed wire passing therethrough so that an inspector can readily tell the valve has been tampered with if the seal is broken. 30

No amount of movement of the lever arm 16, after the valve is once closed, can possibly open it again.

Having now described my invention, what I claim and desire to be protected in, by Letters 35 Patent, is:

1. In a shut-off valve having temperature actuated closing mechanism, the combination of a valve body head in which is formed a control chamber and a valve stem chamber, a spring loaded valve stem and valve disc mounted in said valve stem chamber, said stem extending upwardly into said control chamber and having an odd pitched thread formed upon its upper end, an adjustable contact disc mounted upon said odd pitched thread, a cam having a dependent lever arm extending downwardly into said valve stem chamber mounted in said control chamber adjacent to said contact disc, said cam and lever arm adapted to support said disc and spring loaded valve stem in the valve open position when said cam and lever arm are in a fixed position, a threaded boss formed exteriorly upon said valve body head adjacent the bottom thereof, a fusible plug mounted upon the outer end of said boss and retained thereon by a screw cap, said fusible plug comprising an abutment to one end of a slideable control rod mounted in the center of said boss while the opposite end of the rod extends interiorly into said valve stem chamber and forms an abutment to the lower end of said lever arm to retain the latter in a fixed position whereby said spring loaded valve stem is retained in the open position.

spring loaded valve stem in the valve open position when said cam and lever arm are retained in a fixed position by a slideable control rod mounted in the wall of said valve stem chamber adjacent to the bottom thereof, said control rod having a valve head formed upon the inner end thereof and a stem extending through the said wall and a boss formed exteriorly thereon and having its outer end abutting upon a fusible plug secured upon the outer end of said boss by a screw cap whereby the inner end of said control rod comprising said valve head forms a stop to the lower end of said lever arm to retain the latter in a fixed position to support said spring loaded valve stem in valve open position, the inner wall of said valve chamber having a seat for said valve head.

3. In a glandless shut-off valve having temperature actuated closing mechanism, the combination of a valve body head divided into a control chamber and a valve stem chamber, a spring loaded valve stem and disc mounted in said valve stem chamber, said valve stem extending upwardly into said control chamber and having adjustment means mounted thereon, a cam having a dependent lever arm extending downwardly into said valve stem chamber mounted adjacently to said adjustment means in said control chamber, said cam having a shoulder formed upon the top thereof to provide a buttress to a helical compression spring mounted intermediately of said buttress and the adjacent inner wall of said control chamber whereby turning movement is imparted to said cam and dependent lever arm when free to move, said cam and lever arm adapted to support said adjustment means in the valve open position when said cam and lever arm are retained in a fixed position by a valve headed control rod forming a stop to the lower end of said lever arm, said valve headed rod having a seat formed upon the inner wall of said valve stem chamber for the head of said control rod to seat upon when the latter is subjected to movement, said control rod having a stem slideable in and

extending through the wall of said valve stem chamber and a boss formed exteriorly thereon and having its outer end abutting upon a fusible plug mounted upon the outer end of said boss, whereby said control rod is restrained from movement and forms a stop to the lower end of said lever arm to retain the latter in a fixed position whereby the cam upon the upper end of said lever arm is caused to support the spring loaded valve stem in the valve open position.

4. In a glandless shut-off valve having temperature actuated closing mechanism the combination of a valve body head divided into a control chamber and a valve stem chamber, a spring loaded valve stem and disc mounted in said valve stem chamber, said valve stem extending upwardly into said control chamber and having adjustment means for supporting said valve stem mounted thereon, a cam having a dependent lever arm extending downwardly into said valve stem chamber mounted adjacently to said adjustment means in said control chamber, said cam having a shoulder formed upon the top thereof to provide a buttress to a helical compression spring mounted intermediately of said buttress and the adjacent inner wall of said control chamber whereby turning movement is imparted to said cam and dependent lever arm when free to move, said cam and lever arm adapted to support said adjustment means in the valve open position when said cam and lever arm are retained in a fixed position by a slideable control rod mounted in the wall of said valve body head and intermediately of an insulated fusible plug and the lower end of said lever arm, being connected in an electric circuit which is grounded upon said shut-off valve, whereby upon said circuit being closed by the temperature closing the mechanism through a temperature rise said fusible plug will be fused to a degree to release said control rod whereby said cam and dependent lever arm are released from their fixed position and permit said spring loaded valve stem and disc to close the valve.

CHARLES RAYMOND ROSS.
